DESIGN FOR A COMBINED BOTTLE AND STOPPER

John D. Buckingham, Chicago, Ill., assignor to
Lucien Lelong, Inc., Chicago, Ill., a corporation
of Illinois

Application January 26, 1942, Serial No. 105,437

Term of patent 14 years

To all whom it may concern:

Be it known that I, John D. Buckingham, a citizen of the United States and a resident of the city of Chicago, in the county of Cook and State of Illinois, have invented a new, original, and ornamental Design for a Combined Bottle and Stopper, of which the following is a specification, reference being had to the accompanying drawing, forming a part thereof.

On the drawing:

Figure 1 is a front elevational view of the combined bottle and stopper showing my new design;

Figure 2 is a side elevational view; and

Figure 3 is a plan view of the bottle portion only of the combined bottle and stopper.

I claim:

The ornamental design for a combined bottle and stopper, as shown and described.

JOHN D. BUCKINGHAM.
